UNITED STATES PATENT OFFICE.

JOHN ALGOTS, OF CHICAGO, ILLINOIS.

DESIGN FOR A BIN-COVER.

SPECIFICATION forming part of Design No. 34,146, dated February 26, 1901.

Application filed November 14, 1900. Serial No. 36,532. Term of patent 7 years.

To all whom it may concern:

Be it known that I, JOHN ALGOTS, a citizen of the United States, and a resident of Chicago, in the county of Cook and State of Illinois, have invented and produced a new and original Design for Bin-Covers, of which the following is a specification, reference being had to the accompanying drawings, forming a part thereof.

10 In the accompanying drawings, Figure 1 is a side elevation of a bin-cover made according to my new design. Fig. 2 is a perspective view of said cover.

15 The leading or material feature of my design consists in a bin-cover having a rear part with a swell or hump extending along the top and a lid forward of said rear part and having a swell or hump extending along and near said rear part and substantially parallel with 20 the hump on said rear part.

The lid or front part of the cover shown is

made of sheet metal and has its lower face 1 substantially flat. The upper face rises gradually from the front edge 2 to form the hump or swell 3 toward the rear edge 4 of said lid. 5 5 represents a button or knob for raising the lid. The hump or swell 3 of the lid is designed to rest in the depression 8 of the part 6 and against the front of the hump on the part 6 when the cover is raised or tilted back 30 on its rear edge 4. Said rear edge will be hinged to the part 6.

What I claim as new, and desire to secure by Letters Patent, is—

The design for a bin-cover, substantially as 35 herein shown and described.

Signed by me at Chicago, Illinois, this 22d day of October, 1900.

JOHN ALGOTS.
